ILLUMINATED MUSIC LYRES

Curtis W. Roseberry, Leesville, La., assignor of
forty-nine per cent to Jay Gethren Palmer,
Leesville, La.

Application August 8, 1940, Serial No. 351,832

3 Claims. (Cl. 240—6.4)

The present invention relates to improvements in illuminated music lyres, and more particularly relates to that type of small lyre carried directly upon the musical instrument for holding the music in position to be read by the player while marching on parade.

The primary object of the invention is to provide such a lyre with illuminating means for illuminating the music sheets at night and when playing in dark places where music stands cannot be used such as in a stadium at night.

A further object of the invention is to provide a small, neat and inexpensive attachment for the present form of lyre which will aid in the support of the music sheets and will also add materially to the strength of the lyre while providing the necessary illumination.

A still further object of the present invention is to provide a small and easily handled illuminated lyre construction in which the illumination is procurable by the use of replaceable dry batteries at small cost and wherein the lighting of the lyre is controlled externally by a conveniently operable switch that forms an unobtrusive part of the construction.

An important object of the invention is to provide a separable lamp, battery and switch assembly which may be attached to and detached from the lyre in a quick and easy manner and in which when in place the unit will tend to reinforce the back plate of the lyre which carries the unit.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a side elevation of a musical instrument and lyre with the device attached which is constructed in accordance with the present invention.

Figure 2 is a fragmentary view, on an enlarged scale, of the front of the lyre showing the attachment in place with parts broken away and parts shown in section.

Figure 3 is a similar view taken from the back of the device and the lyre.

Figure 4 is a vertical section taken on the line 4—4 in Figure 2.

Figure 5 is a horizontal cross-section taken on the line 5—5 in Figure 2.

Figure 6 is a rear elevation of a portion of the

lyre showing the initial contracted condition of the spring clamps in the act of assembly, and Figure 7 is a cross-section taken on the line 7—7 in Figure 2.

5 Referring more particularly to the drawing 10 represents an upright casing or barrel of metal or other appropriate material in which one or more dry battery cells 11 are removably contained, such batteries being of a usual form 10 found on the open market for use in connection with flash lights. Such cells 11 are supported upon a coil spring 12 mounted within a hollow cap 13. Across the flange of the cap and through the coil spring 11, anchoring such coil spring to 15 the cap, is a cross pin 14 having outwardly projecting ends at diametrically opposite points of the flange for the purpose of entering bayonet slots 15 in the lower portion of the casing 10. The flange of the hollow cap 13 slidably fits 20 within the lower open end of the casing 10.

The spring 12 serves to snap the cross pin ends into the locking sockets of the bayonet slots, which condition is shown in Figures 2 and 3. By pushing upwardly upon the hollow cap 13 and retaining the same the pin ends will 25 be free of the bayonet slots permitting of the downward removal of the cap and spring assembly thus permitting of the removal of the battery units and their replacement whenever the same have become exhausted.

30 Batteries of course are in electrical connection as usual. The top terminal 16 of the battery is shown as placed in close proximity to a spring terminal 17 normally biased to an upper non-contacting relation with battery terminal 16. Switch blade 18, is mounted for rotation cross-wise of the casing 10 and in position with 35 relation to spring terminal 17 that when in the position indicated in Figure 4, the flat side of the switch blade 18 will be presented to spring terminal 17, thus permitting the inherent resiliency of the terminal to break contact with the battery terminal 16. When, however, the switch 40 blade 18 is rotated through an angle of 90° from Figure 4 the broad side of the blade will be brought downwardly against spring terminal 17 forcing the same down upon battery terminal 16 and thus completing the circuit of the lamp.

45 The rotary switch blade 18 may be conveniently rotated by an external rotary operating knob 19. The spring terminal 17 is upon the lower end of a bow 20 held in place by a screw 21. This screw has its headed portion lying within a lamp socket 22 in which is removably screwed a lamp 23.

55

The lamp socket is contained in a housing 24, the axis of which is at substantially right angles to the axis of the tubular upright casing 10. Within the housing 24 is an internal shoulder 25 against which fits an insulating washer 26 which is external of the lamp socket. Within the lamp socket is another insulating washer 27; the screw 21 passes through the base of the lamp socket and through both of said insulating washers and draws these three parts against the shoulder 25. The screw 21 also has electrical contact with the bow 20 and the head of the screw forms the base terminal for engagement by the terminal of the lamp 23.

As shown in Figure 3 wings or flanges 28 of the casing 24 receives screws or other fastenings 29 by which a reflector casing 30 is secured upon the housing 24. The lower portion of the reflector casing 30 is open and light shields 31 and 32 project downwardly therefrom with the shield 31 bent at a greater angle from the openings of the casing than the outer shield 32 in order to shield the eyes of the musician and to throw the illumination from the lamp 23 directly upon the music held in the lyre.

A top flanged plug 33 is fitted removably in the upper end of the upright casing 10 and carries the bow 20 and receives therethrough the screw 21 and the rotary switch blade 18. This switch blade may be withdrawn laterally from the top plug 33 and from the casing 10; and after the screws 29 are removed and the reflector casing 30 separated from the housing 24 the lamp bulb 23 may be unscrewed from the lamp socket 22 giving access to the head of the screw 21. By unscrewing this screw 21 with the aid of a screw driver such screw 21 may be withdrawn from the plug 33 and from the casing 10, this allowing the plug to be lifted out. The housing 24 fits at its inner end into a circular opening made in the side walls of the casing 10 as shown in Figure 4.

The lyre stem is indicated at 34, the same having a foot 35 removably received in the detent 36 mounted upon the musical instrument 37 shown in Figure 1.

The back of the lyre is usually constructed with a central bar 38 with openings 39 at the sides thereof, such openings being in turn flanked by the side bars 40. The usual spring lyre music clamp is indicated at 41.

The upright casing 10 carries a sheet metal spring 42 secured by fastenings 43 to the front side of the housing 10 near its lower end. Such sheet metal spring extends around the casing in both directions from the point of fastening 43 and involves side members 44 which extend along the sides of the casing and project tangentially rearward therefrom, as indicated in Figure 5, to a plane spaced from the rearmost portion of casing 10. Here the side members 44 are outturned to form the outturned clamp members 45, such members extending in opposite directions. Such outturned clamp members have inclined edges 46, as shown more particularly in Figures 2 and 6, thus the clamp members are wide at their lower ends and progressively narrow to the upper parts thereof for the purpose of agreeing generally with the form of the openings 39 in the back of the lyre.

In the use of the device, the casing 10, housing 24 and lamp reflector 30 with their interior parts constitute a lamp assembly which may be quickly attached to or detached from the lyre back by the use of the spring clamp arrangement.

The side members 44 of the clamp may be 75

engaged by the thumb and fingers of one hand and pressed together, as shown in Figure 5, against the sides of the casing 10, in which position the clamp members 45 are brought together in the position shown in Figures 5 and 6. This enables the clamp members 45 to line up with and to enter the openings in the back of the lyre. The wide lower portions of clamp members 45 are preferably introduced at the lower portions of the lyre openings.

Once the clamp members 45 have entered the openings, the casing 10 may be raised and the grip upon side members 44 released. The spring clamp will then open causing the members 45 to spread out and to engage the bars 40 as shown in Figures 2 and 3. The fastenings 43 being in line will not interfere with the resiliency of the side members 42. The clamp members 45 are carried upon the free ends of these side members 44. As shown in Figure 6 the clamp members 45 are of less height than the openings in the back of the lyre so as to enable the clamp members to interlock with the lyre bars in the upper position of the clamp members in such openings.

As shown in Figure 4 the casing 10 lies closely along the back of the lyre to a relatively long substantially vertical line to reinforce and strengthen the back of the lyre against any weakening influence incident to its support of the lamp assembly unit.

By squeezing together the side members 44 and lowering the casing 10 the unit may be quickly removed from its engagement with the lyre. The lamp may be illuminated by a quarter turn of the switch knob 19 and as easily extinguished. It will be appreciated that all of the parts are readily accessible for replacement and repair and for the renewal of batteries and that the device is quickly put in place and removed from the lyre.

It is obvious that various changes and modifications may be made in the details of construction and design of the above specifically described embodiment of this invention without departing from the spirit thereof, such changes and modifications being restricted only by the scope of the following claims.

What is claimed is:

1. In combination with a lyre light, a hollow casing lying along the rear of said lyre, means for holding said casing on said lyre, batteries in said casing, a housing projecting at substantially right angles forwardly from the upper portion of said casing, a light reflector removably carried by said housing, said light reflector having an opening in its lower portion, light shields at opposite sides of said opening, a lamp socket in said housing, a lamp in the reflector removably mounted in said socket, and electrical and switch connections between said lamp and said batteries.

2. In combination with a music lyre, a hollow casing, means for supporting said casing from said lyre, batteries in said casing, said casing having an opening in its side wall at its upper portion, an open ended housing having an end fitted in said opening, a lamp socket in said housing, a lamp in said socket, a light reflector on said housing extending about said lamp, an internal shoulder in said housing adjacent the casing, a fastening member passing through the base of said lamp socket, insulating members at opposite sides of the lamp socket base, one of said insulating members abutting against said internal shoulder, a contact member in electrical connection with said screw and mounted in said casing in proximity to a terminal of said battery, and switch means

mounted through the casing for causing said electrical connection to contact said battery terminal.

3. In combination with a music lyre, a casing, means for holding said casing upon said lyre, batteries in said casing, a flanged plug in the upper end of said casing, a bow spring contact member carried in said plug and having a lower spring terminal end biased out of contact with the battery terminal, a rotary flat switch blade mounted through said casing in working relation to said

5 spring terminal, a housing extending off from said casing near its upper end, a lamp socket in said housing, a lamp in the socket, a reflector on the housing extending about said lamp, and a fastening member for holding the lamp socket in the housing and for drawing the housing against the casing, said fastening passing through said plug and said bow spring contact member.

CURTIS W. ROSEBERRY.
